UNITED STATES PATENT OFFICE.

JOSEPHINE L. HOLT, OF OAKLAND, CALIFORNIA.

DESIGN FOR A DOLL.

Application filed August 7, 1926. Serial No. 18,630. Term of patent 3½ years.

To all whom it may concern:

Be it known that I, JOSEPHINE L. HOLT, a citizen of the United States, residing at Oakland, in the county of Alameda and State of California, have invented a new, original, and ornamental Design for a Doll, of which the following is a specification, reference being had to the accompanying drawing, forming part thereof.

Figure 1 is a front elevation of a doll, showing my new design, and

Figure 2 is a side elevation of the same.

I claim:

The ornamental design for a doll as shown.

JOSEPHINE L. HOLT.
